UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

LOOPER MECHANISM FOR SEWING MACHINES.

1,213,424.

Specification of Letters Patent. Patented Jan. 23, 1917.

Application filed March 9, 1914. Serial No. 823,409.

To all whom it may concern:

Be it known that I, DUDLEY S. SEYMOUR, a citizen of the United States, residing at Oak Park, in the county of Cook, State of Illinois, have invented certain new and useful Improvements in Looper Mechanisms for Sewing-Machines, of which the following is a description, reference being had to the accompanying drawing and to the figures of reference marked thereon.

The invention relates to new and useful improvements in looper mechanisms for sewing machines, and more particularly to the mechanism for positively moving the looper back and forth in one direction relative to the needle.

An object of the invention is to provide means for adjusting the throw of the looper without varying the timing thereof relative to the movements of the needle.

A further object of the invention is to provide means for adjusting the position of the eccentric for vibrating the looper and for holding said eccentric in adjusted positions.

These and other objects will in part be obvious and will in part be hereinafter more fully disclosed.

In the drawings, which show by way of illustration only one embodiment of the invention, Figure 1 is a part plan view and part sectional view showing a looper, a looper support, and the means for vibrating the looper. Fig. 2 is a sectional view on an enlarged scale showing the looper vibrating mechanism. Fig. 3 is a transverse sectional view through the work support showing the looper vibrating mechanism in side elevation. Fig. 4 is a transverse sectional view showing the operating shaft, the supporting collar for the eccentric and the adjusting means for shifting the eccentric. Fig. 5 is a perspective view of the supporting collar, the eccentric and the adjusting means. Fig. 6 is a detail showing the cylindrical bed in end view. Fig. 7 is a diagrammatic view showing the path of movement of the looper point in different adjusted positions.

The invention consists, generally, in providing an eccentric which gives only one of the movements to the looper, which eccentric may be adjusted relative to the shaft for varying the throw of the looper.

A supporting collar is attached to the shaft and the eccentric is so connected to

said collar as to turn therewith, and this eccentric is shifted transversely of the shaft on said collar by a shifting screw.

Referring more in detail to the drawings, I have shown the invention as applied to a sewing machine having a cylindrical bed 1 which projects laterally from the standard 2 carried by the supporting base 3. Extending longitudinally through the cylindrical bed 1 is a looper support 4, see Fig. 2. 60 This looper support is mounted in suitable bearings in the cylindrical bed and the looper 5, see Fig. 1, is pivotally mounted on a carrier attached to said looper support 4. The looper is so positioned as to move into 70 and out of a needle loop in a plane which extends longitudinally of the looper support 4. The looper is oscillated back and forth into and out of the needle loop by a link 6 which is operated from a cross shaft 75 in the standard 2.

The looper support 4 is oscillated so as to give a needle avoiding movement to the looper. This is accomplished through an eccentric 7 with which operates an eccentric 80 strap 8. The eccentric strap 8 is pivoted, at 9 to an arm 10 which is clamped to the looper support 4. This arm is preferably split, as at 10, and a clamping bolt 11 serves to clamp said arm on to the looper support 4. The 85 eccentric is actuated by a shaft 12 which may be rotated or which may be oscillated from suitable means in the standard 2. The present type of machine is provided with an upper rotary shaft which operates the cross 90 shafts in the standard and these cross shafts in turn operate the looper and the feeding mechanism of the sewing machine.

The shaft 12 is provided with a collar 13 which is rigidly attached to the shaft by a 95 set screw 14. The eccentric 7 is formed integral with a sleeve 15. Said sleeve and eccentric are each provided with an elongated opening 16 through which the shaft 12 extends. This elongated opening permits the 100 sleeve and the eccentric to be moved transversely of the shaft for varying the eccentricity of the eccentric and thereby varying the effective throw thereof.

The collar 13 has laterally projecting 105 parts 17 and these parts are slotted, as at 18. Said slots 18 are parallel with each other and are elongated. Bolts 19 extend through these slots into the sleeve 15. When said bolts are loosened, the sleeve can be ad- 110

justed transversely of the collar and by tightening said bolts, the parts may be firmly locked together. The sleeve 15 also carries a rib 20 which extends into a slot 21 formed in the collar 13. This rib and slot connection serves to firmly hold the sleeve and collar so that the eccentric will be rotated or oscillated with the shaft, partaking of the movements of the collar 13 which is fixed to the shaft. The upper end of the slot is bridged by a plate 22. A screw 23 extends through said plate and a collar 24 on the screw engages the under face of the plate while the head of the screw engages the upper face of the plate. This permits the screw to turn and holds the same from endwise movement. The screw is threaded into the rib 20.

When it is desired to adjust the throw of the looper, the bolts 19 are released and by turning the screw 23 said collar 15 and the eccentric carried thereby will be moved positively transversely of the shaft. The movement of the screw one way will increase the throw of the eccentric as the center of the eccentric will thereby be moved farther from the center of the shaft, while a movement of the screw in the opposite direction will decrease the throw of the eccentric.

When the eccentric is adjusted the proper distance, the bolts 19 will be set up in order to hold the parts firmly in adjusted position. This adjustment of the eccentric varies the throw of the eccentric without varying the timing thereof. In other words, the maximum throw of the eccentric will always be in the same angular position, and, therefore, the lateral throw of the looper may be adjusted without varying the timing of the throw relative to the reciprocations of the needle. Furthermore, the adjustment of the throw of the looper is accomplished by positive means. Not only is the eccentric released so that it can be adjusted, but I have provided a screw for accomplishing this adjustment, so that I have means for making the adjustment as well as means for permitting the adjustment of the throw of the looper.

In Fig. 7 of the drawings, I have shown diagrammatically the path of movement of the looper point in different adjusted positions. The curved line *a*—*b*—*c*—*d* indicates one path of movement of the looper, and the curved line *a*—*c*—*c*—*f* indicates the path of movement of the looper after its throw has been adjusted by shifting the eccentric away from the center of the operating shaft. It will be apparent from this diagrammatic view, that the lateral throw of the looper has been adjusted without in any way varying the timing of the looper in its movements into and out of the needle loop. This looper-operating mechanism with the adjusting means, is especially adapted for use

in a multiple needle machine. When the needles are changed, and a needle of larger diameter used, then it is essential that the path of movement of the looper shall also be changed, so that the looper point may move close to the needle as it enters the needle loop. Where a plurality of needles are used, it is essential that the looper when entering the needle loops shall be traveling substantially in a straight line, so as to pass close to each needle.

It will be seen from the diagrammatic view of the path of movement of the looper, that the looper is given a movement substantially in a right line as it is passing so into each of the needle loops, and when the lateral throw of the looper is varied upon the change of the needles, the looper still moves in the desired coöperative relation to the needles.

It is obvious that minor changes in the details of construction and arrangement of parts may be made, without departing from the spirit of the invention as set forth in the appended claims.

Having thus described my invention, what I claim as new and desire to secure by Letters Patent, is:—

1. A sewing machine including in combination, a needle, a looper, means for vibrating the looper into and out of the needle loop, means for moving the looper laterally including a shaft, devices operated by the shaft, means for adjusting said devices, and means for holding said devices in adjusted position.

2. A sewing machine including in combination, a needle, a looper, means for vibrating the looper into and out of the needle loop, means for moving the looper laterally including a shaft, an eccentric, means for supporting said eccentric on said shaft, whereby the same may be adjusted transversely of the shaft for adjusting the lateral throw of the looper.

3. A sewing machine including in combination, a needle, a looper, means for vibrating the looper into and out of the needle loop, means for moving the looper laterally including a shaft, an eccentric carried by said shaft, means for adjusting said eccentric transversely of the shaft, and means for holding the eccentric in adjusted position.

4. A sewing machine including in combination, a needle, a looper, means for vibrating the looper into and out of the needle loop, means for moving the looper laterally including a shaft, a collar mounted on said shaft, an eccentric supported and actuated by said collar, and means for shifting said eccentric on said collar transversely of said shaft.

5. A sewing machine including in combination, a needle, a looper, means for vibrating the looper into and out of the needle

loop, means for moving the looper laterally including a shaft, a collar mounted on said shaft, an eccentric supported and actuated by said collar, means for shifting said eccentric on said collar transversely of said shaft, and means for holding said eccentric in adjusted position.

6. A sewing machine including in combination, a needle, a looper, means for vibrating the looper into and out of the needle loop, means for moving the looper laterally including a shaft, a collar fixed to said shaft, an eccentric attached to said collar and adjustable transversely of the shaft, a screw 15 for adjusting said eccentric on said collar, and clamping bolts for holding said eccentric in adjusted position.

7. A looper mechanism for sewing machines, comprising a looper support, a looper mounted thereon, means for oscillating said looper support including a shaft, a collar mounted on said shaft, an eccentric, a sleeve attached to said eccentric and having a rib adapted to engage a slot in said collar, said 25 sleeve and eccentric having an elongated opening therethrough, whereby said sleeve and eccentric may be adjusted transversely of the shaft on said collar, means for ad-

justing said sleeve transversely of the shaft, and means for clamping said sleeve to said 30 collar.

8. A looper mechanism for sewing machines, comprising a looper support, a looper mounted thereon, means for oscillating said looper support including a shaft, a collar 35 mounted on said shaft and having a slot extending diagrammatically across the same, an eccentric, a sleeve carried on said eccentric and having a rib adapted to engage said slot, said collar having slots formed therein 40 and at each side of said diametrical slot and parallel thereto, clamping bolts located in said last named slots and engaging the sleeve for clamping the sleeve to said collar, a plate bridging said slot in the collar, an adjustable screw having spaced members engaging said plate for preventing endwise movement of said screw, said adjusting screw being threaded into said sleeve, whereby said sleeve 45 may be positively adjusted on the collar. 50

In testimony whereof, I affix my signature, in the presence of two witnesses.
